TROLLEY SWITCH AND FROG

Leland L. Davis, Kansas City, Mo., assignor to
 The Ohio Brass Company, Mansfield, Ohio, a
 corporation of New Jersey

Application November 26, 1940, Serial No. 367,203

5 Claims. (Cl. 191—38)

My invention relates to overhead electrically operated switches which are particularly adapted for use in an overhead system for the operation of the trolley bus employing two current collectors.

One object of my invention is to provide an electrically operated overhead trolley switch to guide one or two current collectors on a moving vehicle along the main trolley wires at a branch point in the overhead construction or onto the branch trolley wires.

Another object of my invention is to provide a switch for use at the junction of main and branch conductors in which the setting of the switch for guiding the current collectors therethrough is controlled by the direction of travel of the vehicle upon which the current collectors are mounted, at the time of passing the switch.

Another object of my invention is to provide an overhead electrically operated trolley switch provided with a pair of shunt coils to operate the tongues of the switch to either of its two positions and including means to interrupt the flow of current to the coils after operating the switch to prevent overheating and damage to the coils.

A further object of my invention is to provide an electrically operated trolley switch arranged with tongues to guide the current collectors on a moving vehicle, with means to open the circuits to the electrically operated mechanism for positioning the switch tongues to prevent overheating of the mechanism and also to provide means to prevent or reduce the arc which would otherwise form upon opening the circuits and thereby destroy the contacts.

A further object of my invention is to provide an electrically operated overhead trolley switch in which the electrically operated mechanism for positioning the tongues is provided with protecting means, the said means comprising auxiliary switching means to interrupt the flow of current to the operating mechanism to prevent damage to the mechanism from overheating and including a condenser to prevent or reduce the arc which would otherwise form at the opening of the switch.

A still further object of my invention is to provide means to discharge the condenser after absorbing the energy produced by interrupting the current flow to the electrically operated mechanism.

Another object of my invention is to provide an overhead electrically operated switch provided with tongues to guide the current collectors on

a moving vehicle and a plurality of operating coils therefor, with a single auxiliary switch to interrupt the flow of current to the operating coils in order to protect the operating coils from overheating and to provide a single condenser to eliminate or greatly reduce the arcing at the auxiliary switch to prevent damage to the contacts at the points of break.

Another object of my invention is to provide a switch having two electrically operated frogs for use on an overhead system employing two trolley wires of opposite polarity whereby the current collectors on a moving vehicle are guided through the switch in predetermined paths and in which is employed a single mechanically operated auxiliary switch to control the energization of the operating mechanism of both frogs and means associated with the frogs to insure operation of both frogs before the auxiliary switch effects the deenergization of the electrically operated mechanism.

Another object of my invention is to provide the aforementioned condenser with means to limit the discharge current thereof to prevent burning and pitting of the contacts of the auxiliary switch upon closing the same.

Other objects and advantages will appear as the description of the particular physical embodiments selected to illustrate the invention progresses, and the novel features will be particularly pointed out in the appended claims.

My inventions herein disclosed relate to new and novel constructions, combinations, and relations of the parts described in this specification and shown in the drawings forming a part thereof.

In the drawings:

Fig. 1 shows a schematic arrangement of one form of my invention employing shunt operating coils as applied to trolley bus operation for a left-hand turn-out in which the movement of the frog tongues is controlled by the direction of travel of the vehicle relative to the main trolley wires and shows the relation of the parts after a bus has passed straight through the switch.

Fig. 2 shows schematically the same switch as in Fig. 1 but shows the relation of the parts after a bus has passed through the switch and onto the branch wires.

Fig. 3 shows a top view of a single frog arranged for a right-hand turn-out with the cover partly removed to show the tongue operating mechanism and aforementioned auxiliary switch.

Fig. 4 is a side view of Fig. 3.

Fig. 5 is an end view of Fig. 3.

Fig. 6 is a section on the line 6—6 of Fig. 3. Fig. 7 is a side view in partial section of the auxiliary switch referred to hereinabove.

Fig. 8 is a top view of Fig. 7. Fig. 9 is an end view of Fig. 7.

Fig. 10 is another end view opposite to Fig. 9 in partial section of the auxiliary switch, showing one relation of the parts to the operating lever when the frog tongue is midway between its two guiding positions.

Fig. 11 is an end view in partial section corresponding to the end view of Fig. 10, but showing the relation of the parts to the operating lever when the frog tongue is in one of its two guiding positions.

Fig. 12 is a partial section on the line 12—12 of Fig. 10.

Fig. 13 is a schematic arrangement of a modified form of my invention employing shunt and series operating coils and showing the relation of parts after a bus has passed straight through the switch.

Fig. 14 is a schematic arrangement of my invention shown in Fig. 13 but showing the relation of parts after a bus has passed through the switch along the turn-out.

Electrically operated switches for use in overhead trolley systems for operating trolley buses employing two current collectors are now in use but such switches lack certain refinements and improvements which are required to make them more practical and to meet ever increasing advancements.

My inventions are shown schematically in Figs. 1, 2, 13, and 14 and are adapted for use in an overhead trolley system employing a pair of trolley wires of opposite polarity and are arranged to be positioned at turn-out points in the system.

In the preferred embodiment of my invention, I provide a switch comprising a pair of trolley frogs F—F' held in spaced relation by insulators 1. The frogs are provided with a pan 2—2' and movable tongues 3—3' respectively. The tongues are pivotally mounted and movable to either of two positions, one as shown in Fig. 1 which is the straight through position and the other as shown in Fig. 2 which is the turn-out position.

To the frog F is secured the main trolley wire 4 and the branch wire 5; to the frog F' is secured the main trolley wire 4' and the branch wire 5'. The tongues 3—3' guide the current collectors 6—6' along the main wires or from main to branch trolley wires as required.

Frog F is provided with two coils and a plunger for operating the tongue to either of its positions depending upon which of the coils is energized. These coils in the arrangement shown in Figs. 1 and 2 are shunt coils, that is, they are wound to be connected between the main trolley wires without the addition of resistance. As shown, the coil S which is mounted on the pan 2, when energized, will move the plunger or magnetic core 7 to the left and through the medium of mechanism shown in Figs. 3 and 4 and later described the tongue 3 which is pivoted to the pan 2 at 9, will be moved to the straight through position as shown in Fig. 1.

When the coil T is energized the plunger 7 will be moved to the right and the tongue 3 moved to the turn-out position as shown in Fig. 2.

The coils S—S' of the frogs F—F' respectively are connected in parallel and the same is true of the coils T and T'. The coils S—S' of the two frogs and the coils T and T' of the two frogs may be connected in series, if desired, in which case

the resistance of each coil will be substantially one-half that of coils constructed to be connected in parallel across the trolley wires.

The plungers 7 and 7' are preferably slidably positioned in a brass or copper tubing 10—10' respectively and the tube 10' is slotted longitudinally at 11 as later explained.

The description above is directed particularly to the frog F but the frog F' is equipped in like manner and the parts described function as those of frog F.

My invention is installed at the junction of the branch trolley wire with the main trolley wire. To control the operation of the switch, 15 I install in the trolley wire 4 a contact A and in the trolley wire 4', a pair of longitudinally arranged contacts B and C. The contacts A and B are so positioned longitudinally relative to each other on the approach side of the switch that the contacts will both be in engagement with the current collectors 6 and 6' as the trolley bus turns to take the turn-out as shown schematically in Fig. 1 by the dotted line and arrow X, but the contacts A and B will not be in engagement with the current collectors 6 and 6' at the same time if the bus operator intends the bus to pass straight through the frogs along the main wires as indicated by the dotted lines and arrow Y.

Further, the contacts A and C are so placed longitudinally relative to each other that they will both be in engagement with the current collectors 6—6' when the bus operator intends to go straight through the switch but not so if he intends to take the turn-out.

Each contact is so constructed and arranged relative to its trolley wire that it will be energized while the current collector is in engagement therewith as the current collector will have simultaneous engagement with the trolley wire.

The contact A is connected to both coils on both frogs since it plays a part in the operation of the switch when the bus passes straight 45 through the switch or takes the turn-out.

To effect proper energization of the coils on both frogs, the contacts A, B and C are connected thereto as follows: The conductor 12 connects the contact A with the auxiliary or circuit control 50 switch D (later described).

The switch D is connected with the coils S and S' by the conductor 13 and with the coils T and T' by the conductor 14. The coils S and S' are connected with the contact C by the conductor 15 and the coils T and T' are connected with the contact B by the conductor 16.

The auxiliary switch D in general comprises two sets of contacts each set constituting what might be termed sub-switches d and d' respectively for controlling the circuits to the coils. When the contacts of d are opened, the contacts of d' are closed and vice versa (see Figs. 1 and 2), and one purpose of the switch D is to open the circuit to the energized coils on the two frogs after the tongues have been properly positioned to prevent overheating and damage to the coils should the current collectors come to rest while in engagement with the contacts A, B and C and simultaneously close the circuit to the other pair of coils and place them in condition to be energized later.

The auxiliary switch D may be operated directly by the plunger 7, but I prefer to use the lever arm 17 which is secured to the tongue at 9 and, therefore, moves with the tongue.

The switch D, as later explained, is mounted upon the frog F as is the case with the coils S and T. The switch D is insulated from the frog F as indicated by the insulation 18, and from the lever 17 by the insulating knob 19. The blade 20 makes and breaks contact with the fixed contact 21 and the blade 20' makes and breaks contact with the fixed contact 21'.

It will be noted that the insulating member 19 is of less length than the space between the blades 20 and 20', therefore, when the tongue 3 is in its intermediate position between its extreme guiding positions, the blades 20 and 20' will each be in engagement with its contact 21 or 21' respectively, thus connecting the contacts 21 and 21' momentarily while the tongue moves between its extreme positions since the blades 20 and 20' are connected at one end.

The purpose of providing a momentary connection of fixed contacts 21 and 21' is to aid in the use of a condenser across the breaks when the contacts of d and d' open the circuit. I have found that a condenser across the contacts at d and d' will prevent or reduce the arcing at the opening of the contacts and this is very advisable, because such arcing would very shortly destroy the contacts since the system employs as a rule 600 volts between trolley wires and any flash would linger for a considerable time.

I find with the arrangement of the circuits as shown, one switch D is sufficient to control all coils on both frogs and that with the switch D as constructed a single condenser 22 will control the arcing at both sets of contacts at d and d' as the short-circuiting of the contacts momentarily will dissipate or discharge the charge taken up by the condenser at the separation of the contacts under load.

When the lever 17 is moving between its limits, there is during a period of time during the travel of the lever when the both sets of contacts at d and d' will be closed at the same time, thus short-circuiting the condenser through the resistance 23. The resistance 23 limits the rate of discharge of the condenser and prevents burning of the contacts of the sub-switches d and d' which would otherwise take place if the full discharge of the condenser were permitted at d or d' just prior to the closing of the contacts thereof.

The resistance 23 is relatively small and, therefore, it has little effect upon the rate of charge of the condenser 22 or upon its absorption of a charge but it is of sufficient resistance to effectively limit the discharge current from the condenser to a value consistent with the current carrying ability of the contacts.

Since the condenser is shorted at each operation of the tongue and of the switch D, it is only necessary to use one condenser and one resistance to protect the coils of both frogs F and F'.

I prefer to associate the switch D with that contact device (contact A) and with that trolley wire (shown as negative) common to all coils. The condenser 22 absorbs the energy released by the magnetic field upon interruption of the current at d and d'.

The tongues of the two frogs are not mechanically connected; therefore, both tongues are not compelled to move simultaneously. If the operating mechanism of the frog F should respond first and should operate the switch D before the mechanism of the frog F' has operated the tongue on frog F', then the frog tongues would be set at

variance to guide the current collectors to different positions.

To overcome this condition, the metal tubing 10' of the frog F' may be slotted from end to end thus the generation of induced current in the tube, which would otherwise oppose the magnetising effect of the coils S' and T', would be prevented; the unslotted tube 10 of the frog F will act to retard the magnetising effect of the coils S and T due to the induced currents set up in the tube and the heavier the tubing the greater is the retarding effect. Hence the tongue of frog F' would respond to energization of the coils C' and T' before the switch D is operated.

Further, the response of the mechanism on the frog F may be lowered by decreasing the rate at which the magnetic core is magnetised by the use of a shading ring 24 of copper, whereby the rate of increase of the flux in the magnetic circuit is decreased.

The operation of my invention is as follows:— Assuming the frogs set as shown in Fig. 1 and a bus operator approaching the switch is desirous of taking the turn-out, then the bus operator will head the bus in the direction of the turn-out, as shown by X; when the current collectors 6—6' are in engagement with the contacts A and B, current will then flow from trolley wire 4 through contact B, through conductor 16, coils T and T', conductor 14, contacts d', conductor 12, contact A to trolley 4 thus energizing coils T and T' and operating the tongues 3—3' to their turn-out positions. As the bus proceeds the collector 6' will engage the contact C, but the coils S and S' will not be energized because the circuit through the coils S and S' will be opened at the contact A.

Assuming the switch set as in Fig. 1 and the bus operator desires to go straight through as shown by Y; the current collector 6' will energize the contact B from the trolley wire 4' but the coils T and T' will not be energized because the circuit will be opened at A. As the bus proceeds, the current collectors 6 and 6' will energize the contacts A and C respectively, but the circuit through the coils S and S' will be opened at contacts d and the circuit through the coils T and T' will be opened at contact B.

Assuming the setting of the switch as in Fig. 2, and the bus operator desires to go straight through as shown by Y; when the current collector 6' engages and energizes the contact B, the coils T and T' will not be energized because the circuit therethrough will be opened at d', but as the bus proceeds and collectors 6 and 6' will energize contacts A and C respectively and the circuit through the coils S and S' will be completed by way of conductors 15 and 13, sub-switch d, and conductor 12.

Assuming the setting as in Fig. 2 and the bus operator wishes to make the turn as shown by X; the collectors 6 and 6' will energize the contacts A and B respectively, but the circuit through the coils T and T' will be opened at sub-switch d' and the current through the coils S and S' will be open at contact C, and as the bus proceeds and the collector 6' engages the contacts C, the coils S and S' will not be energized because the circuit therethrough will then be open at contact A.

In each operation of the tongue, the auxiliary switch D is operated and the contacts at either d or d' opened under load, but the condenser 22 will absorb the energy either wholly or in part depending upon its capacity, and if the bus

should stop with the current collectors on the contacts the opening of the proper set of contacts at d or d' will prevent overheating the coils.

In the foregoing description, I have described the various essential elements of my invention and the function and operation of the switch as a part of the overhead system with respect to a moving bus. I will now describe the specific form of auxiliary or circuit control switch D which I use, although other forms or modifications may be used which will come within the scope of my invention as later claimed.

The specific construction of the operating mechanism is shown in Figs. 3 to 12 inclusive. Mounted upon the pan 2 is a frame 30 supporting the coils S and T. A yoke 32 is secured to the end plate 31 by the screws 33. The pintle 34 is secured to and pivots with the tongue 3 and projects above the upper surface of the pan 2. Secured to the pintle or stem 34 is a lever 35 (17 in Figs. 1 and 2). Pivotedly mounted on the yoke 32 is a latch 36 under tension of the adjustable spring 37. The projecting end of the magnetic core 7 is attached to the lever 35 intermediate its ends whereby the lever is moved about the axis of the pintle 34 as the core 7 is moved in either direction depending upon which coil is energized. The free end of the lever 35 engages a roller on the latch 36 whereby the lever is releasably held in either of its two positions. The cover 38 protects the mechanism mounted on the pan from the weather.

Associated with the frame 31 is the circuit control switch D held in position by the upper screw 33. In Fig. 7 is shown an enlarged side view of the switch D corresponding to the view of the switch in Fig. 5. The auxiliary switch comprises an angle support 40 with an opening 41 to receive the screw 33 and to receive also the screw 42. Mounted on the support 40 is a second support 43 provided with a slot 44 which permits lateral adjustment along the longitudinal axis of the coils relative to the lever 35. The switch D is held in adjusted position by the screw 42.

Depending from the member 43 is the member 45 of insulating material and held thereto by screws 46. On opposite sides of the member 45 are clamps 47, preferably of insulating material but which may be of metal, and each is provided with a groove to receive the insulated conductors 48 and 49 (conductors 13 and 14 of Fig. 1) and the screw-bolts 50 hold the parts in position.

The member 45 is provided with dovetailed grooves 51, one on each side face thereof and in each groove there is positioned a copper plate 52-52' respectively (21 and 21' of Fig. 1) and to which the conductors 48 and 49 are connected respectively.

Positioned between the members 43 and the block 45 but insulated from the member 43 by insulation 53, is a U-shaped conducting member having depending blades 54-54' (20 and 20' of Fig. 1) of phosphor bronze or resilient copper and connected at one end by a square bend. The blades are provided with contact studs 55-55' to engage the plates 52-52'.

When the switch D is in position as shown in Figs. 3 and 4, the lever 35 is positioned between the blades 54-54' and insulated therefrom by insulation 56, and the lever 35 as it moves in either direction engages the blades to move them to their open position. The insulation 56 may be attached to the blades. In Fig. 10 the lever 35 is shown in mid-position as when the tongue is in mid-position between its extreme or guiding po-

sitions. In Fig. 11 the lever is shown as engaging blade 54' and having broken contact between the blade 54' and the plate 52'.

In Figs. 13 and 14, I show schematically a modified form of my invention in which the switch is operated by what I designate as a "power-on" and a "power-off" method. In this arrangement, I employ shunt coils S and S' respectively for the frogs H and H' and, also, series coils R and R' respectively. The shunt coils automatically position the tongues to either one of their positions as may be predetermined as in the case of the S-S' coils in Fig. 1, and the series coils position the tongues to the other position but require the bus operator to move his controller to one of its "on" positions in order to effect the energization of the coils R-R' which is not the case with the coils T-T' of Fig. 1. I make no claim to the "power-on" and "power-off" idea as the same has been in use for quite some time, but even a switch so operated is very likely to have its shunt coils overheated if subjected to current for too long a time.

I have indicated with like characters certain parts of Figs. 13 and 14 which are common with the disclosure in Figs. 1 and 2 where the parts are the same or function the same. The frog pans 2-2' are held in spaced relation by insulators 1 and each frog is provided with a tongue 3-3' respectively. Associated with the trolley wire 4' is a shunt contact 70 and a series contact 71. The contact 70 is connected to the coils S-S', which are connected in parallel, by the conductor 72. The contact 71 is connected to the series coils R-R', which are connected in series, by the conductor 73. The circuit to the series coils is completed by the conductor 74 which connects the coils to the trolley wire 4' or pan 2'.

The series coils are of much heavier wire than the shunt coils since they must withstand a very happy flow of current when the contact 71 is engaged by the current collector 6' with the controller set to "power-on" but the time of such flow is only while the collector moves across the contact as the current flowing through the coils R-R' also flows through the motors of the vehicle, hence the current collector 6' does not engage the contact 71 with "power-on" for any great length of time as the bus will keep moving.

Since there is little danger of the coils R-R' being overheated, I provide no means to protect them but the shunt coils S-S' are subject to overheating if the bus stops with the collector 6' on the contact 70 which is energized at such times; therefore, I provide an auxiliary or circuit control switch E to open as soon as the coils S-S' have operated to move the tongues to the straight through position as in Fig. 13. The lever 17, which moves with the tongue 3, operates the switch E which comprises the blade 75 and fixed contact 76.

The coils S-S' are connected to the switch E by the conductor 77 and the circuit is completed by the conductor 78 which connects the switch blade 75 to the pan 2 which is of the same polarity as the trolley wire 4; therefore, the knob 19 on the lever 17 which engages with the blade 75 is not insulated as the blade 75 of the switch E is of the same polarity as the pan 2 at all times.

Assuming the parts of the switch are in the relation shown in Fig. 13 then the switch functions as follows when a bus passes the contacts; as the current collector 6' engages the contact 70 the same is automatically energized but the

coils S—S' will not be energized as the circuit is open at E; if the bus operator wishes to go straight through, he then passes the contact 71 with "power-off" and in that case no current will flow through the coils R—R' to energize them sufficiently to operate the switch; if, however, the operator wishes to take the turn-out he throws his controller to "power-on" and the current flows from the charged pan 2', through the conductor 74, coils R—R', conductor 73, contact 71 through the motors and current collectors of the bus to the trolley wire 4, thus properly energizing the coils R—R' and moving the tongues to the turn-out position as shown in Fig. 14.

Assuming the switch is in the condition shown in Fig. 14, then the switch functions as follows when a bus passes the contacts; when the current collector engages the contact 70 it is energized and current will flow through the conductor 12, coils S—S', conductor 71, switch E, conductor 78, to the pan 2, thus automatically energizing the coils S—S' and setting the tongues 3—3' to the straight through position. If the bus operator wishes to go straight through he turns his controller to "power-off," but if he wishes to take the turn he applies "power-on" and when the collector 6' engages the contact 71, current will flow through the conductor 74, coils R—R', conductor 73, contact 71, through the bus motors and current collectors to the trolley wire 4, thus energizing the coils R—R' and returning the tongues to the turn-out position.

In order to protect the contact and blade of the switch E from burning due to arcing when the switch opens under load, I connect a condenser 22 across the break to absorb the energy of the arc, and to limit the rate of discharge of the condenser when the contacts approach in closing, I introduce a resistance 23 in series with the condenser. Any charge in the condenser will be dissipated when the contacts of the switch E engage and the condenser will be ready to absorb the energy of the arc when the contacts separate and thus prevent or reduce the destructive effects of the arc upon the contacts.

Having described my invention, I claim:

1. In an overhead trolley switch employing a pair of trolley frogs each provided with a movable tongue adapted to guide a current collector along a main conductor or on to a branch conductor at a turn-out and electrically operated mechanism for each frog including a pair of coils to operate each tongue in opposite directions, the combination therewith of means to control the energization of the coils of said mechanisms including means associated with one frog and operated by the mechanism thereof to alternate the energization of the coils on each frog and also including means to retard the operation of the mechanism associated with said one frog with respect to the operation of the other mechanism.

2. In a trolley switching system for a pair of current collectors on a trolley bus, in combination, a pair of main trolley wires, a branch wire from each main wire, a trolley frog at each junction of each main and branch wire, each frog having a movable tongue to guide the collectors along the main wires or on to the branch wires, electrically operated mechanism for each frog, each mechanism including a pair of unconnected and opposed coils associated with each frog to operate the tongue thereof to either of its two positions, one coil of each frog connected to the respective or corresponding coil of the other frog whereby each pair of connected coils will be sep-

arately energized, a circuit control means associated with one frog and connected to the coils of both frogs and operated by the mechanism of said one frog to effect the alternate energization of the coils of each frog and move the tongues on both frogs to corresponding positions, contact devices associated with the trolley wires and positioned adjacent the approach side of the frogs, the contact devices being constructed and so positioned with respect to each other and to the trolley wires as to be engaged by and energized by the passing current collectors, the contact devices and the operating mechanism and the circuit control means being so connected that the said coils on both frogs will be so selectively energized as to move the tongue on each frog to one or the other of its positions depending upon the energization of the contact devices, and means associated with each frog to control the rate of energization of the coils of one frog relative to the rate of energization of the coils of the other frog whereby the operation of the mechanism with said one frog will be retarded with respect to the operation of the mechanism of the other frog.

3. A trolley switch for a trolley system employing a pair of main conductors of opposite polarity and a branch wire for each main wire and arranged to guide a pair of current collectors mounted on a vehicle, comprising in combination, a trolley frog at the intersection of each main and branch conductor, each frog provided with a movable tongue forming a guide for the current collectors, electrically operated mechanism for each tongue to operate the tongue to either of its positions, each mechanism provided with a pair of unconnected opposed operating coils to actuate the mechanism in opposite directions, one coil of each frog connected to the corresponding coil of the other frog whereby the connected coils will be energized and de-energized simultaneously, means actuated by a member of the electrically operated mechanism on one frog to effect alternate energization of the connected coils, and means to retard the rate of operation of the electrically operated mechanism associated with the said one frog with respect to the operation of the mechanism of the other frog.

4. A trolley switch for a trolley system employing two trolley conductors of opposite polarity and a branch wire from each trolley wire, the switch having two mechanically connected but insulated frogs each having a movable tongue to guide a pair of current collectors mounted on a vehicle, and each frog provided with electrically operated mechanism to move the tongue thereon to either of two positions, the combination with the electrically operated mechanism of one frog of means operated by the last said mechanism, the said means being electrically connected to each mechanism whereby selective energization of each mechanism is effected to operate the tongues to either of two respective positions, the said means being arranged to effect alternate energization of the mechanism on each frog to move the tongue thereof to either one or the other of its positions, and means associated with and cooperating with the aforesaid one frog to retard the operation of the mechanism thereon with respect to the operation of the mechanism on the other frog.

5. In an overhead trolley switch, in combination, a pair of electrically operated trolley frogs, each frog adapted to guide a current collector along a main wire or on to a branch wire at a

turn-out, operating mechanism on each frog and which includes a pair of opposed coils, the correspondingly operating coils of the two frogs being connected for simultaneous energization and to effect actuation of each frog to either of its two positions, means actuated by the operating mechanism of one frog to effect alternate ener-

gization of the connected coils of each frog and means to control the relative rate of energization of the coils whereby the operation of the operating mechanism associated with the said one frog will be retarded with respect to the movement of the operating mechanism on the other frog.

LELAND L. DAVIS.
